DOOR LOCK

Filed Oct. 20, 1921

12 Inventor
34 Samuel Edelson
By his Attorney Charles G. Kewley

UNITED STATES PATENT OFFICE.

SAMUEL EDELSON, OF NEW YORK, N. Y.

DOOR LOCK.

Application filed October 20, 1921. Serial No. 509,038.

To all whom it may concern:

Be it known that I, SAMUEL EDELSON, a citizen of the United States, and a resident of the city, county, and State of New York, have invented certain new and useful Improvements in Door Locks, of which the following is a specification.

My invention relates to door locks. The object of my invention is to provide a simple and inexpensive lock of strong construction which will protect a door against forcible opening. My improved lock not only prevents the door being swung open on its hinges but it also prevents it from being forced edgewise as by a jimmy or similar instrument. It is common practice for burglars to apply a jimmy to the edge of a door to force the door edgewise, and there is generally sufficient clearance between the door and its frame to permit the door to be forced edgewise sufficiently to allow a knife or other flat instrument to be inserted between the door and the door frame, for the purpose of moving the bolt of the lock back and thus permit the door to be opened. The purpose of my invention is to protect the door from being forced edgewise in the manner described, as well as preventing it from being forced open by a swinging motion; or in other words, to perform the same function as the ordinary lock and in addition, to prevent jimmying. I am aware that locks have been devised to give this double protection, but they have been complicated and expensive and they have complicated mechanism which has to be operated each time the key is turned to lock and unlock the door. In the present lock a single plate and bolts of the simplest construction and operated by simple means of ordinary construction may serve to lock the door, in conjunction with certain locking means on the casing and the sash plate.

In the drawing forming part of this application—

Figure 1—is an elevation of the lock with the cover removed to show the interior mechanism, Figure 2—is a side view of the frame plate or keeper, Figure 3—is a sectional view taken on the line 3—3 of Fig-

ure 1, showing the lock and frame plate or keeper, Figure 4—is a face view of the lock applied to a door, Figure 5—is a side elevation of the frame plate or keeper, Figure 6—is a sectional view showing the bolts and the keeper, Figure 7—is a sectional view on the line 7—7 of Figure 3—and Figure 8 is a plan view of the frame plate or keeper.

I have shown my invention applied to an ordinary swinging door 1 and the door frame plate 2 is attached to the door frame. The door frame plate 2 is here shown as embodying a plate portion 3 which is set into the edge of the door frame 4 near one edge of the door (when the latter is closed) and there are screws 5 passing through this plate and screwed into the door frame to hold the plate in place. There is a housing 6 preferably formed integral with the plate 2 and screws 7 pass through apertures 70 in the wall 8 of this housing and these enter the door frame at right angles to the screws 5 and assist in holding the door frame member in place.

The frame member 2 is so formed as to provide sockets 9 above and below the bolt socket 10. The latter is preferably half round as shown, to conform to the shape of the bolt. The front of the housing 6 is formed with shoulders 11 and 12 and the block 15 is formed with shoulders 13 and 14 which constitute dovetail pockets 16 to receive the male portions of the lock casing, as will appear hereafter.

The lock comprises a casing or shell 17 having a closing cover 19 secured thereto by screws and forming an enclosure 18 in which the mechanism of the lock is enclosed. The lock casing is secured to the door by screws 21 passing through the wall 20 and entering the door.

The lock casing is provided with an extension preferably formed integral therewith. This extension forms an abutment at 23 for one edge of the cover; and it forms a projection which is U shaped as viewed vertically. As viewed from the front, it forms two male members 24, 25 having enlarged outer ends 26 and reduced neck portions 27 constituting dovetail members 100

which cooperate with the dovetail sockets 16 in the door frame member 2.

A single sliding bolt plate 28 may be used for locking the door to reduce the 5 mechanism of the lock to the simplest form. Herein I have shown a horizontally sliding plate 28 with a laterally extended head 29 having three bolt members 30, 31, 32 arranged in a vertical row. The central bolt 10 member 31 is arranged to enter the socket 10 in the block 15 on the door frame member 2. The bolt member 30 enters the cross socket 33 in the housing behind the projections 11, 13. The third bolt member 32 15 likewise enters the socket 34 behind the projections 12, 14 of the housing. The several bolt members are preferably half round in cross section as shown, as this construction of bolt not only strongly resists lateral pressure but the curvature at 35 in the housing makes a strong construction of the projections and the curvatures 36 of the block 15 also makes the construction of this block 20 strong for the quantity of metal used.

25 Any form of mechanism may be used for operating the bolt plate. I have shown the plate 28 encircling the axis of the inside knob 37. Pivoted at 38 to the plate 28 is the "dead" locking arm 39 which has a projection 40 to engage on either side of the block 41 of the casing to secure the bolt plate 28 in either projected or retracted position, and the spring 42 presses this member down onto the block but permits it to 30 be raised either by the operation of the knob or the key. This deadlock member has a finger 43 projecting into the path of the arms 44 on the hub 45 of the knob member whereby the member 39 may be rocked to 35 disengage the projection 40 from the block 41—when the knob is turned. This unlocks the plate 28 to permit the bolts to be projected or retracted. The plate 28 has projections 46, 47 which are engaged by the arms 44 so that the plate 28 and the bolts are moved to the right or left when the knob is turned.

There is a barrel 49 containing the usual 50 tumblers and which receives the key, and there is a tongue 50 which is turned by the tumblers and this tongue turns the sleeve 51 on the cover. The sleeve 51 has an arm 52 which operates on the same members as do the arms 44 to release the deadlock member 39 and to shoot the bolts. There is nothing new in this device for operating the bolt plate and so far as my present invention is concerned any other mechanism may be used for the same purpose.

60 *Operation.*—The lock being fastened to the door and the member 2 being fastened to the door frame, each time the door is closed (the bolts being retracted at such times) the projections 24, 25 move into the 65 sockets 16 as a result of the swinging mo-

tion of the door. These projections in entering the sockets 16 in no way impede the movement of the door as they are so proportioned that they enter the sockets without friction. When the door is closed, if 70 it is desired to lock it, either the knob is turned or a key is inserted into the barrel 49 and it is turned, in either case the plate 28 being moved to project the bolts. The bolt 31 will enter the socket 10 and the bolts 30, 32 will enter the sockets 33, 34 respectively. The door is now securely locked in all directions. The door can not be opened by a swinging motion on its hinges because the bolt 31 engages in the socket 10 and because the bolts 30, 32 lie behind the projections—and therefore can not move away from the door frame. There is, therefore, the resistance of the three bolts to any outward swing of the door. The door can not be forced edgewise as by a jimmy because of the dovetail shape of the projections 24, 25 and of the sockets in which they engage. Any edgewise movement of the door is resisted by the enlarged heads 26 engaging the 80 projections of the frame member 2. Therefore, the door is held against movement in all directions. To unlock the door the knob or the key is turned in the reverse direction and this retracts the plate 28 and the bolts. The door may then be swung open freely. 85

With the present device each time the door is closed it is in condition to be locked by the simple operation of projecting the bolts and this locks the door against movement in every direction.

Having described my invention what I claim is:—

1. A lock comprising a member adapted to be secured to the door frame and having interlocking, dovetail sockets adapted to receive projections on the lock casing in one direction, and having sockets to receive bolts in another direction, a lock casing having interlocking, dovetail projections adapted to enter said dovetail sockets as the door is closed, and sliding bolts movable in said dovetail projections into and out of said bolt sockets in said first member, said bolts projecting laterally beyond said dovetail projections.

2. A lock comprising a member adapted to be secured to the door frame and having interlocking, dovetail sockets to receive projections on the lock casing in one direction, and having sockets to receive bolts in another direction, a lock casing having interlocking, dovetail projections of substantially U shaped cross section, adapted to enter said dovetail sockets, and bolts sliding in said dovetail projections and adapted to enter said bolt sockets, said bolts projecting laterally beyond said dovetail projections.

3. A lock comprising a member adapted to be secured to the door frame and having

a block provided with a socket to receive a bolt and having interlocking dovetail sockets above and below said socket to receive projections on the lock casing as the door is swung closed, a lock casing having interlocking, dovetail projections of substantially U shaped cross section, adapted to enter said dovetail sockets, a plate and a

plurality of bolts thereon, one of which is adapted to enter the socket in said block and the others being adapted to slide in said dovetail projections and to interlockingly engage said first member.

Signed at the city, county and State of New York, this 8th day of October, 1921.

SAMUEL EDELSON.
